UNITED STATES PATENT OFFICE.

ALFRED G. ANDERSON, OF NEW YORK, N. Y.

DESIGN FOR A BRIDGE-LAMP DISPLAY FIXTURE.

Application filed June 26, 1928. Serial No. 27,292. Term of patent 3½ years.

To all whom it may concern:

Be it known that I, ALFRED G. ANDERSON, a citizen of the United States, residing at New York city, in the county and State of New York, have invented a new, original, and ornamental Design for a Bridge-Lamp Display Fixture, of which the following is a specification, reference being had to the accompanying drawing, forming part thereof.

Figure 1 is a plan view; and
Figure 2 is a side elevational view, showing my new design.

I claim:

The ornamental design for a bridge lamp display fixture, as shown.

ALFRED G. ANDERSON.
